UNITED STATES PATENT OFFICE.

HAROLD B. FITZ GERALD, OF GLENRIDGE, NEW JERSEY.

STARTER FOR TALKING-MACHINES.

1,084,420.

Specification of Letters Patent. Patented Jan. 13, 1914.

Application filed April 3, 1913. Serial No. 758,609.

To all whom it may concern:

Be it known that I, HAROLD B. FITZ GERALD, a citizen of the United States, and a resident of Glenridge, in the county of 5 Essex and State of New Jersey, have invented a new and Improved Starter for Talking-Machines, of which the following is a full, clear, and exact description:

This invention relates to improvements in 10 starters for talking machines, and has for an object to provide an improved structure which will instantly start the record moving at any time automatically so that when the device is once set, no further attention need 15 be paid the same.

A further object of the invention is to provide a starter for the records of graphophones, which is associated with the alarm mechanism of a clock, and is designed to 20 lock the record against movement until the alarm mechanism of the clock operates, whereupon the record is instantly unlocked and caused to start so that when the entire arrangement has been once set, the same will 25 remain in that condition until the time indicated, whereupon the record will begin to move for reproducing the sound in the usual manner.

In carrying out the objects of the invention, a record of any desired kind may be 30 used, as for instance a disk record, with which the starting device is associated. The starting device is formed with a pivotally mounted handle carrying at its outer end a 35 spring, on which is arranged a buffer designed to engage the disk. The buffer, spring, and arm are arranged to lock the disk against movement until the same is moved, whereupon the disk is moved 40 pivotally for a short distance and then to move under the usual power provided therefor in a talking machine. The pivotally mounted arm is arranged on a base which is adapted to receive a clock, the clock having the alarm 45 mechanism thereof connected with the arm so as to actuate the same at any desired time.

A practical embodiment of the invention is represented in the accompanying drawings forming a part of this specification, in 50 which similar characters of reference indicate corresponding parts in all the views.

Figure 1 is a top plan view of an embodiment of the invention, a fragmentary view 55 of the disk record being shown in connec-

tion therewith; Fig. 2 is a side view of the structure shown in Fig. 1, a clock being shown in an operative position; Fig. 3 is a view similar to Fig. 2, with certain parts broken away for showing the connection 60 between the alarm arbor of the clock and the actuating arm of the starter; Fig. 4 is a top plan view of the base and clock supporting member; and Fig. 5 is a perspective view of the starter arm.

Referring to the accompanying drawings by numerals, 1 indicates a disk record of any desired kind designed to be actuated in the usual manner of records. Arranged to contact with the disk 1, is a buffer 2 formed of yielding material, as for instance rubber or leather. This buffer is mounted upon a spring 3, which in turn is rigidly secured to arm 4 by any desired means, as for instance a screw 5. The spring 3 is bowed so as to cause buffer 2 to press against disk 1 when in the position shown in Fig. 1, but to readily bow as arm 4 moves from the position shown in full lines in Fig. 1 to the dotted position. As the arm 4 moves, the same will 75 cause a movement of disk 1 and will cause the buffer 2 to be moved out of contact with disk 1, as clearly shown in dotted lines in Fig. 1.

In setting the device, the usual lock for 85 holding disk 1 stationary, is released and buffer 2 is arranged as shown in full lines in Fig. 1. By this arrangement the disk 1 is ready to move, but is locked against movement by buffer 2 and associated parts. The 90 movement of buffer 2 and associated parts by the alarm mechanism of clock 6 will cause disk 1 to move a short distance immediately upon the actuation of the alarm mechanism. This starting of the disk will 95 allow the usual driving mechanism of the disk to further operate the same.

In order that the arm 4 may properly operate, the same is mounted upon a stub shaft 7, formed preferably integral with the 100 base 8, which in turn is preferably cast integral with support 9. In forming the support 9 the same is provided with a groove 10 and a cut-away portion 11, the groove 10 accommodating the clock 6, as shown in Fig. 105 3, and the cut-away portion 11 permitting a free swinging movement of arm 4. The end of arm 4 opposite spring 3 is formed with an enlargement 12 formed with an aperture 13 arranged with the walls thereof in 110

scallops 14, these scallops being arranged in pairs so as to accommodate the ring 15 of the alarm mechanism of clock 6.

In operation, the clock 6 is wound up in the usual manner and the alarm mechanism is also wound and set so as to operate at a certain time. The ring 15 connected with the alarm mechanism is then inserted in aperture 13, as shown in Fig. 3, and the clock 6 is caused to rest upon the shoulder 10. Previous to placing the clock in position, the arm 4 must be moved to the position shown in full lines in Fig. 1. When the device is arranged in this manner it is properly set and will need no further attention until the same has operated. A quick and accurate starter is thus provided for a graphophone and may be used at any time and under various circumstances, as desired.

It will be understood that there may be slight changes made in the detail construction, and various forms of clocks and winding rings 15 may be used, without departing from the spirit of the invention.

Having thus described my invention I claim as new and desire to secure by Letters Patent:—

1. In a starter of the class described, the combination with a clock having an alarm mechanism, of a lever connected with said alarm mechanism, a spring connected with said lever, and a yielding buffer connected with said spring designed to engage and turn a talking machine record carrier.

2. In a starting device for the record carrier of talking machines, the combination with a clock provided with an alarm arbor, of a lever loosely connected with said alarm arbor, a spring rigidly secured to said lever, and a yielding buffer secured to the end of said spring designed to engage the record carrier of said talking machine for starting the same immediately upon the operation of the alarm arbor of said clock.

3. In a starter of the class described, a buffer, a spring connected with said buffer, an arm connected with said spring, said arm being formed with an enlargement at the end opposite said spring and said enlargement being formed with an aperture therein having scalloped walls, a base for supporting said arm, and means engaging the scal-

loped walls of said enlargement for actuating said arm.

4. In a starter for talking machines, the combination with a clock formed with an alarm mechanism, of a swinging arm loosely and removably connected with and actuated by said alarm mechanism, and a buffer connected with the outer end of said arm designed to engage and move for a predetermined distance the record carrier of said talking machine.

5. In a starting device for talking machines, a pivotally mounted arm formed with an enlarged end having an aperture therein formed with notches radiating therefrom, means engaging said notches for swinging said arm from one position to the other, and resilient means connected with the outer end of said arm designed to engage and actuate the record carrier of said talking machine.

6. In a starting device for the record carriers of talking machines, the combination with a clock having an alarm arbor, of a swinging arm connected with said alarm arbor and actuated thereby, a substantially S-shaped spring connected at one end of said arm and a yielding buffer connected at the opposite end of the spring designed to engage and move said record carrier when said arm is actuated by said alarm mechanism.

7. In a starter for the record carriers of talking machines, a swinging arm, resilient means arranged at the outer end of said arm for engaging and moving the record carrier of said talking machine when said arm is moved, a base having a journal pin engaging said arm for pivotally mounting the arm, said base being formed with a clock-receiving socket, and a clock mechanism provided with an alarm arbor loosely and removably engaging said arm whereby when said alarm arbor is actuated said arm will be swung.

In testimony whereof I have signed my name to this specification in the presence of two subscribing witnesses.

HAROLD B. FITZ GERALD.
